UNITED STATES PATENT OFFICE.

WALDO H. MARSHALL, OF NEW BRIGHITON, NEW YORK, ASSIGNOR TO W. V. KELLEY, OF CHICAGO, ILLINOIS.

DESIGN FOR A TENSION MEMBER FOR CAR-BOLSTERS.

SPECIFICATION forming part of Design No. 27,100, dated May 25, 1897.

Application filed January 29, 1897. Serial No. 621,358. Term of patent 14 years.

To all whom it may concern:

Be it known that I, WALDO H. MARSHALL, a citizen of the United States, residing at New Brighton, county of Richmond, State of New York, have invented and produced a new and useful Design for a Tension Member for Car and Truck Bolsters, of which the following, taken in connection with the accompanying drawing, is a specification.

10 The leading features of my design consist in its peculiar configuration and outline, which comprises a V-shaped strap having overturned ends lying approximately in the same plane and pointing toward each other, 15 which gives to the tension member a characteristic and distinguishing appearance.

The design is illustrated in the accompanying drawing, in which the tension member is in the form of a strap 1, bent in the middle 20 to substantially a V shape and having its ends 2 turned to the same side and then back to-

ward each other, so as to lie approximately in the same plane, but at an angle to the V-shaped body portion.

My design discloses a tension member which 25 presents to the eye a characteristic and distinguishing appearance, varying from other designs of tension members for car and truck bolsters particularly in having a V-shaped body and inwardly - extending overturned 30 ends which form an angle with the V-shaped body portion.

What I claim as new, and desire to secure by Letters Patent, is—

The design for a tension member for car and 35 truck bolsters, substantially as herein shown and described.

WALDO H. MARSHALL.
